UNITED STATES PATENT OFFICE.

WILLIAM J. RAINES, OF PHILADELPHIA, PENNSYLVANIA.

CHURCH COMMUNION TRAY AND FILLING DEVICE.

1,416,126.

Specification of Letters Patent. Patented May 16, 1922.

Application filed November 12, 1919. Serial No. 837,580.

To all whom it may concern:

Be it known that I, WILLIAM J. RAINES, a citizen of the United States, residing at #4823 N. Lawrence Street, Philadelphia, 5 in the county of Philadelphia and State of Pennsylvania, have invented a new and useful Improvement in a Church Communion Tray and Filling Device, of which the following is a specification.

10 My invention relates to a church communion tray and filling device, and the object of my invention is to provide a device for quickly filling the cups or receptacles and for readily handling the trays and 15 the container from which the receptacles are to be filled, more fully hereinafter described and claimed.

Referring to the accompanying drawing, Fig. 1 is a perspective view of my improved 20 communion tray and filling device, having a revolving tray; Fig. 2 is a perspective view of my device, showing a different form of valve adapted for use with a stationary tray; Fig. 3 is a vertical, longitudinal sectional 25 view of the valve shown in Fig. 1, drawn on a larger scale, and also showing a transverse section of the valve, taken on a plane extending through the aperture 19 of Fig. 3; Fig. 4 is a vertical, longitudinal sectional 30 view of Fig. 1, with the container and valve removed; Fig. 5 is a side elevation and also an end view of a different form of valve.

Referring to the accompanying drawing, in which like reference characters refer to 35 like parts, 1 represents the base for supporting the tray carrying the cups and also supporting the jar or container from which the cups are to be filled.

Secured upon the base 1 are parallel rails 40 3 upon which is slidably mounted a carriage 12 having posts 13 for retaining the jar upon the carriage, whereby the carriage carrying the jar may be moved into suitable 45 positions for filling the cups arranged upon the tray 6. The rails 3 have horizontal grooves 11 formed in their adjacent faces. The carriage 12 is provided with rollers 14 adapted to occupy the grooves 11 formed in the tracks and thus slidably support the 50 carriage upon the tracks.

The jar or container is provided with a pipe 15 having a valve upon the end thereof, comprising a sleeve 16 having a T-joint connection with the pipe 15, and provided 55 with one or more outlet pipes or nozzles 17

and also provided with a cap for closing the sleeve 16 at one end. The opposite end of the sleeve 16 is open to receive a tubular valve stem 18 having ports 19 and 20 formed therein which register with the inlet port from the pipe 15 and the outlet nozzles 17, respectively. A handle is secured to one end of the valve stem 18 for turning the latter to open and close the ports 19 and 20.

60 The valve, as shown in Fig. 2, may be provided with any number of nozzles corresponding to the number of rows of cups upon the tray, so that the valve may be moved over the cups to fill them without 70 moving the tray in relation to the base 1.

The valve carried by the container may be constructed as shown in Fig. 5, comprising a stop-cock 21, with a fitting 22 thereon, having two nozzles 23 diverging from the 75 fitting 22 so that the open ends of the nozzles will extend over two cups for filling them simultaneously.

The device may be provided with a revolving table 4 as shown in Figs. 1 and 4, 80 suitable for holding a circular tray 6. The table 4 is provided with a central pivot pin 5, adapted to be rotatably mounted in a bushing 2 in the base 1, whereby the table 4 and the tray 6 may be rotated to bring the 85 cups under the nozzles.

The trays are provided with posts 8 for supporting one tray on top of another when it is desired to place several trays in a pile. Upon the under side of each tray 90 are formed recesses 7 into which the posts 8 of another tray will enter and thus hold the trays securely one on top of the other.

The tray 6 is provided with a handle 9 in the form of a ring having an enlarged 95 portion with an aperture formed therein through which a bolt 10 passes. The bolt 10 is rigidly secured in the tray 6 and projects above the tray a slight distance and is provided with a head to retain the 100 handle 9 thereon. The handle 9 will always be held in a vertical position upon the bolt and when not in use will assume the position shown in Fig. 4, and thus permit one tray to be placed on top of another tray. 105

The tray shown in Fig. 2 has the receptacles arranged in rows extending parallel with the direction in which the carriage is movable. The tray is not intended to revolve but is adapted to be placed upon 110

the base in such a position that the rows of receptacles thereon will extend parallel with the movement of the nozzles when the container is moved upon its support. The 5 base is made to act as a guide for readily placing the tray in a suitable position for filling the receptacles.

Having thus described my invention, I claim and desire to secure by Letters Patent:

- 10 1. A church communion tray and filling device comprising a base, a tray adapted to be placed upon a portion of the base, said base having another portion extending beyond the said portion carrying the tray,
- 15 panels secured in a vertical position upon the last mentioned portion of the base and forming supports extending in parallel relation to each other, a carriage slidably mounted upon the said panels, a container 20 adapted to rest upon the upper surface of the carriage and freely removable therefrom, an outlet pipe extending from the side wall of the container and adapted to extend

over the edge of the carriage and over the tray, a valve upon the said outlet pipe and 25 means upon the carriage for engaging the container and holding it in alignment with the tray.

2. A church communion tray and filling device comprising a base, supports upon said 30 base forming tracks, a carriage slidably mounted upon said tracks, said supports having horizontal grooves formed in adjacent faces thereof, members upon the carriage adapted to occupy the said grooves to 35 prevent the carriage from lifting off the supports, a container adapted to rest upon the carriage and freely removable therefrom, an outlet pipe extending from the side wall of the container and adapted to extend 40 over the carriage, a valve upon the outlet pipe, and a tray carrying receptacles adapted to be placed adjacent to the base whereby the receptacles may be filled by moving the carriage in relation to the tray.

WM. J. RAINES.
